STREET SIGN BRACKET

Jack W. Reeves, 3120 NW. 36th, Oklahoma City, Okla.

Filed Apr. 13, 1964, Ser. No. 79,461

Term of patent 14 years

(Cl. D54—1)

FIG. 1

FIG. 2

FIG. 3

FIG. 4

FIG. 1 is a perspective view of a street sign bracket showing my new design.

FIG. 2 is a perspective view of the bracket looking upwardly at the bracket.

FIG. 3 is an elevational view taken at one end of the bracket.

FIG. 4 is an elevational view taken ninety degrees from the view of FIG. 3.

I claim:

The ornamental design for a street sign bracket, as shown.
